[57] **CLAIM**

The ornamental design for fridge door organizer, substantially as shown and described.

DESCRIPTION

FIG. 1 is an end elevational view of a refrigerator door organizer showing my new design;

FIG. 2 is a isometric view thereof;

FIG. 3 is an end elevational view thereof, of the opposite side of FIG. 1;

FIG. 4 is a top plan view thereof;

FIG. 5 is a front elevational view thereof;

FIG. 6 is a rear elevational view thereof;

FIG. 7 is a bottom plan view thereof;

FIG. 8 is a front elevational view of a second embodiment thereof; and

FIG. 9 is a front elevational view of a third embodiment thereof.

The undisclosed portions of FIGS. 8 and 9 are the same as those shown in FIGS. 1, 3, 4, 6 and 7.

FIG. 3

FIG. 2

FIG. 1

FIG.4

FIG.5

FIG.6

FIG.7

FIG.8

FIG.9
